REFRIGERATING APPARATUS

Richard S. Gaugler, Dayton, Ohio, assignor to
General Motors Corporation, Dayton, Ohio, a
corporation of Delaware

Application March 28, 1934, Serial No. 717,703
Renewed August 29, 1936

10 Claims. (Cl. 62—105)

This invention relates generally to refrigeration and particularly to ice freezing apparatus.

An object of the present invention is to provide an improved freezing apparatus which continuously produces ice cubes or blocks after being initially rendered operative without further manipulation or attention on the part of the user.

Another object of the invention is to utilize a force created by the buoyant effect of a predetermined ice formation on a cooling element of a freezing apparatus to automatically and intermittently render the cooling element ineffective for forming ice thereon.

A further object of the invention is to utilize the force created by the buoyant effect of a predetermined formation of ice on a cooling element of a freezing apparatus to cause movement of the element automatically into a position to render same ineffective and to cause ice cubes or blocks to be released therefrom without materially increasing the temperature of the cooling element.

In carrying out the foregoing objects it is a further object of the invention to render the cooling element effective automatically after ice formed thereon has been released therefrom to provide a continuous operating freezing apparatus.

A still further and more specific object of the invention is to provide a freezing apparatus with a plurality of movable cooling or freezing elements which normally assume a position to permit ice to form thereon and which after a predetermined amount of ice has formed thereon will move automatically and independently of one another into a position to cause the ice to be liberated therefrom.

Further objects and advantages of the present invention will be apparent from the following description reference being had to the accompanying drawings, wherein a preferred form of the present invention is clearly shown.

In the drawings:

Fig. 1 is a diagrammatic illustration of a refrigerating system employed for refrigerating the cooling or freezing elements of my apparatus;

Fig. 2 is a top view partly in section and partly in elevation of my freezing apparatus;

Fig. 3 is an enlarged vertical sectional view of the freezing apparatus taken on line 3—3 of Fig. 2 and showing ice beginning to accumulate on one of the cooling or freezing elements;

Fig. 4 is a view similar to Fig. 3 and shows one of the cooling or freezing elements of the ap-

paratus in a position to cause ice formed thereon to be liberated therefrom;

Fig. 5 is an enlarged vertical sectional view of one of the cooling elements of the apparatus and is taken on line 5—5 of Fig. 4; and

Fig. 6 is an enlarged vertical sectional view of one of a plurality of shut off devices employed in the refrigerating apparatus.

In freezing apparatuses heretofore employed for producing large quantities of ice blocks or cubes, such for example as in restaurants, hotels and the like, it has been customary to freeze water in a plurality of metallic receptacles or trays similar to the process carried out in household refrigerator cabinets. The difficulties encountered in harvesting ice from trays of household refrigerators are believed to be well known to those skilled in the art and these difficulties are inherently present in freezing apparatuses of the type above described and employed for commercial use. The foregoing described method of freezing water into the form of blocks or cubes of ice and harvesting the same greatly impedes serving of cold drinks in such establishments as hotels, restaurants, and the like. To this end I propose a freezing apparatus for use in restaurants, hotels and the like which will continuously and automatically produce an abundance of ice cubes or blocks without the harvesting difficulties heretofore encountered in prior apparatuses.

Referring to the drawings, for the purpose of illustrating my invention, I have shown diagrammatically in Fig. 1 thereof a closed refrigerant circulating system employed to refrigerate or cool the freezing elements of my apparatus. The refrigerant circulating system may be of any conventional type and as disclosed, for illustrating the principles of my invention, the system includes a compressor 10 adapted to be operated by a motor 11 operatively connected with the compressor by belt and pulley connection 12, 13, and 14. Compressor 10 upon being operated by motor 11 draws gaseous refrigerant from a plurality of cooling or freezing elements 15, only one of which is shown in the diagrammatic illustration, through pipe or conduit 16. The gaseous refrigerant is compressed by compressor 10 and is forwarded under pressure to condenser 18 in which the compressed refrigerant is cooled in any suitable or desired manner to liquefy the same. The condensed liquid refrigerant flows from condenser 18 into the receiver 19 where it accumulates or is stored prior to being circulated to one of the freezing elements 15. A pipe or conduit 21 leads from the receiver 19 to the branch con-

duits 23 connected with a plurality of the elements 15. Each branch conduit 23 has a restrictor, expansion device or valve 22 inserted therein for controlling the flow of liquid refrigerant to the elements 15. The expansion devices or valves 22 may be of any conventional form and are preferably, in the present illustration, of the type which is caused to be opened in response to a reduction of pressure in elements 15. It is to be understood that one valve 22 is interposed in each branch pipe 23 leading to each of the elements 15 employed in the apparatus for independently controlling the flow of refrigerant to each independent element 15. It is to be further understood that a plurality of branch conduits 17, connected with conduit 16, leads from each element 15 and each of these conduits 17 have a shut off device 25 inserted therein. The devices 25 control the flow of evaporated or vaporized refrigerant from the freezing elements 15 and are operated in a manner to be hereinafter more fully described. A control switch 27 preferably of the snap acting type, includes electrical contacts 28 and 29 inserted in the power line leading to motor 11. The switch 27 is actuated in response to movement of a bellows 31 connected by pipe 32 to the gaseous refrigerant or low pressure conduit 16. As pressures vary between predetermined limits in conduit 16 the bellows 31 will expand or contract and will consequently actuate the switch 27 to make or break the electrical circuit to motor 11.

The freezing apparatus to which the refrigerating system is connected and which apparatus houses any desired number of the cooling or freezing elements 15, includes insulated walls 36 forming a cabinet 37 having a compartment or container 38 therein. A door 39 located in the top of cabinet 37 provides access to the compartment 38. The compartment 38 is adapted to contain a body of water the level of which is maintained substantially constant by a float valve device 41 of any suitable or conventional structure. The float valve device 41 includes the usual needle valve or the like which controls the flow of water through an inlet pipe 42. An overflow pipe 43 may be provided for the container or tank 38. A manually actuated valve 44 is disposed at any suitable location exteriorly of cabinet 37 and has a pipe connection 45 opening into the bottom of the tank or container 38 (see Figs. 3 and 4) draining the liquid contents of the tank in order to permit cleaning of the tank when desired.

55 Each of the plurality of cooling or freezing elements 15 of the apparatus includes a pair of double-walled members 51 each comprising sheet metal plates 52 and 53 (see Fig. 5). The sheet metal plates 52 and 53 are fashioned or corrugated as at 54 and have their contiguous portions secured together to provide a refrigerant expansion chamber or passages 55 therebetween. The pair of double-walled members 51 of each of the plurality of freezing elements 15 are welded or otherwise suitably secured to opposite sides of a portion of an arm or member 57 pivotally mounted on a shaft 58. The shaft 58 is carried in any suitable manner by the walls 36 of the insulated cabinet 37. The end carrying the members 51 of each of the arms or members 57 is provided with passages 59 of a suitable size and design to register with and connect the refrigerant expansion chambers or passages 55 in each double-walled member 51 together. A pair of fins 61 are secured to opposite sides of and

disposed at right angles to the members 51. A balance weight 62 is formed on or secured to one end of the arms or members 57. The ends of the arms 57 and the members 51 secured thereto are of such weight as to slightly overbalance the ends 62 of arms 57 thereby causing the arms 57 and members 51 to normally assume a tilted position such as is shown in Fig. 3 of the drawings. Flexible refrigerant inlet conduits or pipes 23a extend from the restrictors or expansion valves 22 and connect with the refrigerant passage 59 provided in the one end of arms 57 for directing refrigerant through the expansion passages or chambers 55 in the freezing member 15. Similar flexible conduits 17a extend from the refrigerant passage 59 provided in arms 57 and connect with the shut off device 25. The closed refrigerant circuit from the refrigerant liquefying and condensing unit through the apparatus is thus completed as above described.

20 The shut off devices 25 employed in the apparatus may be of any suitable form and construction and are herein disclosed, in Fig. 6 of the drawings for purpose of illustration, as including a sealed casing 61. Casing 61 has a 25 partition 62 provided therein which divides the interior of the casing into two compartments. The partition 62 is provided with an opening 63 for permitting communication between the compartments formed by partition 62 in casing 61. 30 A valve 64 has a spring 65 normally tending to close same against the walls of opening 63. A stem 66 formed on valve 64 extends through opening 63 and is connected with a shaft 67, extending outwardly of the casing 61, by a flange 35 68. A bellows 69 has its one end secured in any suitable manner to flange 68 and has its other end soldered or otherwise secured to the inner wall of the casing 61 surrounding the point of protrusion of shaft 67 from casing 61. The bellows 69 seals the casing against leakage and permits movement of valve 64 relative to its seat or opening 63. The upper compartment in casing 61 communicates with the flexible refrigerant pipe or conduit 17a while the lower compartment of casing 61 communicates with the refrigerant pipe 17. Operation of the shut off device or devices 25 will be hereinafter more fully described in connection with the operation of the apparatus.

50 The shut off devices 25 are supported in any suitable fashion upon brackets 71 (see Figs. 2, 3, and 4) secured to walls 36 of cabinet 37. Each device 25 is positioned directly above and cooperates with one of the arms 57 so that the stem 67 of device 25 is adapted to be engaged and moved by the weighted end portion 62 of arms 57. A plurality of brackets 72 secured to a wall 36 of cabinet 37 serve as stops for the downward movement of arms 57. Another bracket 73 serves as a mounting for the restrictors or expansion valves 22. A screen 75, carried by brackets 76 mounted on the inner surface of walls 36 of the apparatus, depends to a point adjacent arms 57 and serves to direct ice blocks, 65 to be presently described, toward the front of cabinet 37.

Assuming now that the apparatus is to be put into operation and the freezing elements thereof are in their normal position shown in Fig. 3. Water from any suitable source of supply is admitted to the tank or container 38 through inlet pipe 42 until the level thereof reaches a point sufficient to cause the float valve device 41 to close off the water inlet. The re- 75

frigerant liquefying and condensing unit is then put into operation by closing the electric circuit leading to the control switch 27 and motor 11. Refrigerant in the pipe lines 16 and 32 of the 5 refrigerating system will be at a relatively higher pressure than during operation of the system thus causing expansion of bellows 31 to maintain the electric contacts 28 and 29 closed for completing the circuit to motor 11. Operation 10 of motor 11 and consequently compressor 10 causes refrigerant to be drawn from the elements 15 since all elements 15 are at this time in the position shown in Fig. 3 of the drawings with the arms 57 thereof engaging and forcing stems 15 15 67 of shut off devices 25 in an upward position to maintain valves 64 open. The open position of valves 64 permits communication of the refrigerant expansion passages 55, formed in the double-walled members 51, with the suction line 16 of the refrigerating system. The compressor 10 therefore reduces the pressure or tends to create a vacuum in the low pressure side of the refrigerating system and builds up pressure in the high pressure side thereof. Either the low 20 pressure in the refrigerant expansion chamber 55 of the elements 15 or the high pressure created by the compressor in back of the restrictors or expansion valves 22 causes liquid refrigerant to be expanded through the restrictors or valves 25 22 into the refrigerant expansion chambers 55. Refrigerant upon expanding and vaporizing in the chamber or passage 55 produces a refrigerating or cooling effect of the double-walled member 51 of elements 15 and causes water within 30 the container or tank 38 to freeze on the outer surfaces of the members 51 in the form of ice, indicated by the number 78. This refrigerating effect may be and is preferably confined to the end portions of members 51 or 15 beyond the 35 fins 61 in any suitable manner so as to prevent frosting or ice formation on other parts of the apparatus such as by insulating or coating with rubber or the like the flexible conduits 23a, 17a and the portions of arms 57 through which the 40 expanding refrigerant passes. The ice 78 continues to accumulate or build up on members 15 or 51 as refrigeration therein continues until the buoyancy of the ice formed on any one of the freezing elements 15 increases to such a predetermined degree as to create a force sufficient 45 to cause movement of an arm 57 about its pivotal mounting on shaft 58. This movement of arm 57 causes same to assume a horizontal position such as shown in Fig. 4 of the drawings. 50 It is apparent that this movement of any of the arms 57 away from the shaft or stem 67 of shut off device 25 and into abutting relation with the stops 72 causes the spring 65 in casing 61 of the device 25 to close the valve 64 thus cutting 55 off communication of refrigerant expansion chamber or passage 55 in the freezing element 15, moved under the force created by buoyancy of ice formed thereon. The refrigerating effect of freezing element 15, moved in the manner 60 described, is caused to cease since no evaporated or vaporized refrigerant can be withdrawn therefrom and this element therefore begins to increase in temperature. The fins 61 and the sheet metal members 52 of the double-walled structure 51 are constructed so as to be greater in 65 size than the blocks of ice to be formed and therefore the portions of these elements extend outwardly from the formation of ice 78 thereon into the body of water in tank 38. The fins 61 and 70 52 are constructed so as to have a sufficient 75

portion thereof directly exposed to or in contact with the water in container 38 to cause heat absorbed from the water to break the bond between the ice and the cooling or freezing elements 15 or 51. Thus the fins 61 and sheet metal members 52 of the double-walled structure 51 effectively conduct heat from the water to thaw the ice and to cause the ice to be released from the freezing elements 15. The ice blocks 78 thus released from element 15 rises, due to their 10 buoyancy, to the top of the body of water in container 38. These blocks of ice 78 may then be taken or harvested from the apparatus or cabinet 37 upon opening the access door 39. Screen 75 prevents the ice blocks 78 from traveling to the rear portion of the cabinet 37 thus preventing same from interfering with operation or movement of other parts of the apparatus. After the ice 78 has been liberated from one of the freezing elements 15 in the manner described, the buoyant effect of that element is destroyed and it will move about its pivot automatically into the position shown in Fig. 3. This movement of any of the elements 15 causes the arm 57 thereof to strike and force open valve 64 in the shut off device 25. Thus the refrigerating effect or freezing operation of element 15 is restored to again complete the freezing cycle, above described.

The freezing elements 15 of the apparatus may 30 or may not be moved simultaneously by the force created by the buoyancy of the ice formation. In operation of the apparatus disclosed, it will be apparent to those skilled in the art that, the freezing elements 15 will vary somewhat in the refrigerating effect produced thereby and movement of the elements 15 will therefore ordinarily occur in succession rather than simultaneous. However in either event the control switch 27 of the refrigerating system will cause 35 the refrigerant liquefying and condensing unit to stop operating when the pressure of the refrigerant in the low pressure side of the system has been reduced to a predetermined degree. For example, the control switch 28 will always 40 maintain the electric circuit to motor 11 closed except when all the freezing elements 15 are in the position shown in Fig. 3 of the drawings to thus provide a continuous operating freezing apparatus.

It will be apparent from the foregoing that I have provided an improved freezing apparatus of the continuous type and have provided an apparatus wherein a force created by the buoyant effect of ice formed on the freezing elements 55 thereof is utilized for stopping the refrigerating effect of a certain freezing element to permit release of ice blocks therefrom. My improved continuous freezing apparatus permits certain freezing elements to increase in temperature to 60 cause ice to be released therefrom while at the same time causing a continued refrigerating effect in certain other freezing elements to cause ice to form thereon. My improved continuous freezing apparatus is automatic in operation for 65 producing ice blocks or cubes and needs no attention on the part of the user after being initially rendered operative. This insures the production of an abundance of ice cubes or blocks by the apparatus which can be readily harvested without the difficulties ordinarily encountered in freezing apparatuses heretofore employed.

While the form of embodiment of the invention as herein disclosed, constitutes a preferred 75

form, it is to be understood that other forms might be adopted, all coming within the scope of the claims which follow.

What is claimed is as follows:

5. 1. A continuous freezing apparatus for producing ice blocks including, a container for holding a body of water, a plurality of cooling elements disposed in said body of water, means for refrigerating said plurality of cooling elements to 10 a temperature to cause ice to form thereon, and means for stopping the refrigerating effect of one of said plurality of cooling elements independently of and while the refrigerating effect of other of said plurality of cooling elements continues, said last named means being operable 15 automatically in response to a force created by the buoyancy of ice formed on said one of said cooling elements.

2. A continuous freezing apparatus for producing ice blocks including, a container for holding a body of water, a plurality of cooling elements disposed in said body of water and movably mounted independent of one another, means for refrigerating said plurality of cooling elements 20 to a temperature to cause ice to form thereon, said cooling elements being movable automatically in response to a force created by the buoyancy of ice formed thereon, and means actuated by the movement of any one of said plurality of 25 cooling elements for stopping the refrigerating effect thereof, said last named means operating independently of and while the refrigerating effect of the other of said plurality of cooling elements continues.

35. 3. A continuous freezing apparatus for producing ice blocks including, a container for holding a body of water, a plurality of cooling elements movably mounted in said body of water, means for directing a refrigerant through said 40 cooling elements to cool same to a temperature to cause ice to form thereon, said cooling elements being movable automatically in response to a force created by the buoyancy of ice formed thereon, a plurality of valves cooperating with 45 said plurality of cooling elements, and either of said plurality of valves being actuated by the movement of its cooperating cooling element for controlling the circulation of refrigerant therethrough, and said either of said plurality of valves 50 operating independently of other of said plurality of valves to cause the refrigerating effect in the cooling elements cooperating with the said other of said plurality of valves to continue.

4. In the art of making and harvesting ice by 55 producing a freezing action in a plurality of cooling elements submerged in a body of water, that step which comprises utilizing a force created by the buoyant effect of ice formed on one of the plurality of cooling elements for stopping the 60 freezing action therein independently of and while the freezing action continues in other of said plurality of cooling elements.

5. In the art of making and harvesting ice by 65 producing a freezing action in a plurality of cooling elements submerged in a body of water, that step which comprises utilizing a force created by the buoyant effect of ice formed on one of the plurality of cooling elements for causing movement thereof and stopping of the freezing action

therein independently of and while the freezing action continues in other of said plurality of cooling elements.

6. A freezing apparatus for making and harvesting ice blocks including a plurality of cooling elements disposed in a body of water, means for producing a freezing action in said plurality of cooling elements, and means for temporarily interrupting the freezing action in one of said plurality of cooling elements while the freezing 10 action being produced in other of said elements continues, said last named means being operable automatically in response to a force created by the buoyant effect of ice formed on said one of said cooling elements. 15

7. In the art of making and harvesting ice by producing a freezing action in a plurality of cooling elements submerged in water, that step which comprises utilizing the amount of ice formed by one of a plurality of cooling elements for stopping 20 the freezing action thereof independently of and while the freezing action of another of said plurality of cooling elements continues.

8. A freezing apparatus for making and harvesting ice blocks including a plurality of cooling elements submerged in water, means for causing said plurality of cooling elements to produce a freezing action, and means for temporarily interrupting the freezing action produced by one of said plurality of cooling elements while the freezing 25 action being produced by another of said elements continues, said last named means being normally ineffective and rendered effective automatically in response to the amount of ice formed 30 by said one of said cooling elements. 35

9. A freezing apparatus for making and harvesting ice blocks including a plurality of cooling elements submerged in water, conduit means for circulating a refrigerating medium through said cooling elements to cause same to produce a freezing action, a valve interposed in said conduit means for stopping the flow of refrigerating medium through one of said plurality of cooling elements while the freezing action being produced by another of said elements continues, and 40 said valve being normally ineffective and rendered effective automatically in response to the amount of ice formed by said one of said cooling elements. 45

10. A refrigerating apparatus comprising in 50 combination, a plurality of cooling elements, at least one of said cooling elements being submerged in water and adapted to have ice blocks formed thereon, means operable for circulating a cooling medium through said plurality of cooling 55 elements to cause same to produce a refrigerating effect, means for interrupting the refrigerating effect produced by said one of said plurality of cooling elements without interrupting operation of said cooling medium circulating means to thereby permit continuance of the refrigerating effect produced by another of said elements and to cause ice blocks to be released from said one cooling element, and said interrupting means being normally ineffective and rendered effective automatically in response to the amount of ice formed 60 by said one of said cooling elements. 65

RICHARD S. GAUGLER.
